LOOPER MECHANISM FOR SEWING MACHINES

Sydney Zonis, Bridgeport, and Arthur S. Meloy, Jr., Stratford, Conn., assignors to The Singer Manufacturing Company, Elizabeth, N. J., a corporation of New Jersey

Original application March 1, 1941, Serial No. 381,242. Divided and this application April 11, 1942, Serial No. 438,520

5 Claims. (Cl. 112—201)

This invention relates to looper mechanisms for sewing machines, and more particularly to actuating mechanisms for rotary loopers of the conventional wing-type and complementary to an eye-pointed needle in enchaining loops of needle-thread.

The object of this invention is to provide a looper mechanism adapted to be easily assembled as a unit construction and embodied in a sewing machine capable of high speed operation. Other and more specific objects of the invention will be apparent from the following description and claims.

This application is a division of our prior patent application Serial No. 381,242, filed March 1, 1941, the present invention consisting in the provision of a looper mechanism assembly unit as hereinafter described in connection with the accompanying drawing, which illustrates a preferred embodiment of the invention and in which:

Fig. 1 is a vertical longitudinal section of the bed-plate and a portion of the bracket-arm of a sewing machine containing the improved looper mechanism, the needle and presser-foot of the machine being shown in front side elevation. Fig. 2 is an enlarged longitudinal section of the looper mechanism assembly unit, the section being taken in a plane containing the axes of rotation of the looper- and stub-shafts. Fig. 3 is an enlarged section, transversely of the bed-plate, of the lubricant-containing casing housing the looper-shaft driving gearing.

The sewing machine in part illustrated in the drawing has a frame including a work-supporting bed-plate 1, from one end of which rises a hollow standard 2 of a conventional bracket-arm. The bed-plate 1 is provided with the usual throat-plate 3 having a needle-aperture 4. Operating through the throat-plate aperture 4 is an eye-pointed thread-carrying needle 5 carried by a vertically endwise reciprocating needle-bar 6.

The work is advanced past the stitch-forming mechanism by a feed-dog 7 of the drop-feed type and which may be actuated in any usual or suitable manner. The feed-dog 7, which operates through the suitably slotted throat-plate 3, is opposed in its work-engaging movement by a presser-foot 8.

Complementary to the needle 5, in the formation of chain stitches, is a conventional wing-type rotary looper 9. The looper 9 has a shank-pin 10 secured by screws 11 in one end of a longitudinal bore 12 of a tubular looper-shaft 13. The 55

looper-shaft 13 extends horizontally lengthwise of the bed-plate 1 and is rotatably journaled in needle-roller bearings 14 disposed at the opposite ends of a bearing-bore 15 provided in a bushing 16 eccentrically of the longitudinal center line of said bushing. The looper 9 is spaced from one end face of the bushing 16 by a collar 17 secured upon the looper-shaft 13 by the looper-shank fastening screws 11; said collar 17 functioning to confine the looper-shaft 13 against endwise movement in one direction, and also serving to confine the needle-roller bearing adjacent said collar.

The looper-shaft 13 extends entirely through the bushing 16 and carries a gear-wheel 18 externally of and adjacent the end face of the bushing opposite the looper 9; said gear-wheel being preferably integral with the looper-shaft 13. Adjacent the gear-wheel 18, the looper-shaft 13 has a shoulder 19 confining the other of the needle-roller bearings 14 of the looper-shaft.

In driving engagement with the looper-shaft gear-wheel 18 is an intermediate gear-wheel 20 integral with or otherwise carried by one end of a horizontal stub-shaft 21 disposed substantially parallel to the looper-shaft 13. The stub-shaft 21 is also rotatably journaled in needle-roller bearings 22 disposed in the opposite ends of a longitudinal bore 23 provided in the bushing 16 eccentrically of the longitudinal center line of the bushing. The intermeshing gear-wheels 18 and 20 are both disposed within the extended or produced circumferential bounds of the bushing 16, i. e., said gear-wheels are both disposed within the field of the projected end face of the bushing. The stub-shaft 21 also has a roller-bearing confining shoulder 24 at the gear end of said stub-shaft. The other end of the stub-shaft 21 extends beyond the opposite end of the bushing 16 and carries a collar 25 secured upon said stub-shaft 21 by a screw 26.

The looper-shaft 13, the looper 9 carried thereby, and the stub-shaft 21, together with the intermeshing gears 18 and 20, and the roller-bearings for said shafts, may be assembled in the bushing 16 to form a separate assembly unit as illustrated in Fig. 2 of the drawing. As the gears 18 and 20 do not extend radially beyond the circumferential bounds of the bushing 16, the bushing may be endwise inserted into a horizontal opening 27 of a casing-wall 28 depending from the bed-plate 1. The bushing 16 is adjustably secured by a screw 29 in the casing-wall 28 so that the gears 18, 20 are disposed at the side of said wall opposite the looper 9.

The intermediate gear-wheel 20 is engaged by an elongated driving spur-gear 30. The hub 31 of the spur-gear 30 is secured by a screw 32 upon one end of a horizontal bed-shaft 33 disposed substantially parallel to the looper-shaft 13 and stub-shaft 21. Adjacent the spur-gear 30, the bed-shaft 33 is rotatably journaled in a horizontally disposed bearing-bushing 34 suitably secured in another wall 35 of the casing depending from the bed-plate 1; said casing also including a front wall 36 and a rear wall 37. A bottom closure-plate 38, secured by screws 39 to said casing walls, provides a lubricant reservoir 40 housing the gears 18, 20 and 30.

At its opposite end, the bed-shaft 33 is journaled in a ball-bearing 41 supported by a lug 42 depending from the bed-plate 1. Adjacent the ball-bearing 41, the bed-shaft 33 carries a pulley 43 engaged by a belt 44 which is driven to rotate the bed-shaft 33 once for each complete reciprocation of the needle 5.

The hub 31 of the bed-shaft spur-gear is circumferentially recessed to provide a seat for a lubricant-splasher 45 adapted to dip into a supply of lubricant contained in the reservoir 40. The bore 12 of the looper-shaft 13 is provided with a wick 46 protruding slightly from the end of the looper-shaft which extends into the reservoir 40. Lubricant splashed upon the wick 46 is fed thereby lengthwise of the looper-shaft 13 to diametral shaft-apertures 47 leading to the needle-roller bearings 14.

The stub-shaft 21 is also provided with a longitudinal bore 48 provided with a wick 49 extending into the reservoir 40 from the gear end of said stub-shaft; the wick 49 feeding lubricant supplied thereto by the splasher 45 to diametral stub-shaft apertures 50 leading to the needle-roller bearings 22.

Having thus set forth the nature of the invention what we claim herein is:

1. A looper-mechanism assembly unit for chain-stitch sewing machines, comprising, a bushing, a looper-shaft rotatably journaled in said bushing, a rotary looper carried by said shaft, a gear-wheel carried by said shaft, and a second gear-wheel rotatably supported by said bushing in driving engagement with the looper-shaft gear-wheel, said gear-wheels being both disposed within the produced circumferential bounds of the bushing.

2. A looper-mechanism assembly unit for chain-stitch sewing machines, comprising, a bushing lengthwise provided with a bearing-bore, a looper-shaft rotatably journaled in said bearing-bore of the bushing, a looper carried by one end of said shaft, a gear-wheel carried by the

other end of said shaft, and a second gear-wheel rotatably supported by said bushing in driving engagement with the looper-shaft gear-wheel, said gear-wheels being both disposed externally of one end of said bushing within the produced circumferential bounds of the bushing.

3. A looper-mechanism assembly unit for chain-stitch sewing machines, comprising, a bushing, a looper-shaft extending lengthwise of and rotatably journaled in said bushing, a rotary wing-type looper carried by said shaft adjacent one end of said bushing, a gear-wheel carried by said shaft, and a second gear-wheel rotatably supported by said bushing in driving engagement with the looper-shaft gear-wheel, said gear-wheels being both disposed adjacent the end of said bushing opposite the looper end thereof and within the produced circumferential bounds of the bushing.

4. A looper-mechanism assembly unit for chain-stitch sewing machines, comprising, a bushing lengthwise provided with substantially parallel bearing-bores, a looper-shaft disposed in one of said bearing-bores and having a longitudinal bore, a second shaft disposed in the other of said bearing-bores, and having a longitudinal bore, antifriction bearings for said shafts in the bearing-bores of said bushing, a looper carried by one end of the looper-shaft externally of one end of said bushing, a gear-wheel carried by the other end of said looper-shaft externally of the other end of said bushing, a gear-wheel carried by said second shaft and in driving engagement with the looper-shaft gear-wheel, and wicks disposed in the respective bores of said shafts, said shafts having radial apertures leading from the bores of the shafts to said antifriction bearings.

5. A sewing machine having a frame including a bed-plate, a wall depending from said bed-plate having a horizontal opening, a bushing secured in said opening of the bed-plate wall, said bushing being lengthwise provided with a bearing-bore, a looper-shaft rotatably journaled in said bearing-bore of the bushing, a looper carried by one end of said shaft at one side of said wall, a gear-wheel carried by said looper-shaft at the opposite side of said wall, an intermediate gear-wheel rotatably supported by said bushing in driving engagement with the looper-shaft gear-wheel, said gear-wheels being both disposed within the produced circumferential bounds of the bushing, a bed-shaft rotatably journaled in said bed-plate, and a spur-gear carried by said bed-shaft in driving engagement with said intermediate gear-wheel.
